DESIGN FOR A PLATE OR SIMILAR ARTICLE

George Rudd, Bedford, Ohio

Application August 11, 1944, Serial No. 114,839

Term of patent 14 years

(Cl. D44—15)

To all whom it may concern:

Be it known that I, George Rudd, a citizen of the United States of America, residing in Bedford, county of Cuyahoga, and State of Ohio, have invented a new, original, and ornamental Design for a Plate or Similar Article, of which the following is a specification, reference being had to the accompanying drawing, forming part thereof, wherein,

The figure is a plan view of a plate or similar article showing my new design, which is continuously repeated around the rim of the plate to form a complete circle, and a unit of which is outlined in dotted lines.

I claim:

The ornamental design for a plate or similar article, substantially as shown and described.

GEORGE RUDD.

CERTIFICATE OF CORRECTION.

Design No. 139,184.

October 17, 1944.

GEORGE RUDD.

It is hereby certified that the above numbered patent was erroneously issued to the inventor said "RUDD" whereas said patent should have been issued to --The Walker China Co., of Bedford, Ohio--, as assignee of the entire interest therein; and that the said Letters Patent should be read with this correction therein that the same may conform to the record of the case in the Patent Office.

Signed and sealed this 19th day of December, A. D. 1944.
